Primary Examiner — Karen E Eldridge Powers*(74) Attorney, Agent, or Firm* — Gloria Tsui-Yip, Esq.; Gottlieb, Rackman & Reisman, P.C.(57) **CLAIM**

The ornamental design for a brush, as shown and described.

DESCRIPTION

FIG. 1 is a front elevational view of my new design;

FIG. 2 is a rear elevational view thereof;

FIG. 3 is a left side view thereof;

FIG. 4 is a left side elevation view thereof;

FIG. 5 is a right side elevation view thereof;

FIG. 6 is a bottom plan view thereof;

FIG. 7A is a perspective view thereof;

FIG. 7B is an enlarged view of circle A in FIG. 7A; and, FIG. 8 is another perspective view thereof.

The broken-line showing of brush tips in the figures illustrates environmental structure that forms no part of the claimed design.
